(57) **CLAIM**

The ornamental design for a cable connector, as shown and described.

DESCRIPTION

FIG. 1 is a perspective view of a cable connector, showing my new design;

FIG. 2 is a top view of the cable connector shown in FIG. 1; a bottom view of the cable connector shown in FIG. 1 is a mirror image of the top view shown;

FIG. 3 is a front view of the cable connector shown in FIG. 1; FIG. 4 is a left side view of the cable connector shown in FIG. 1;

FIG. 5 is a right side view of the cable connector shown in FIG. 1; and,

FIG. 6 is a rear view of the cable connector shown in FIG. 1. The broken lines showing plug pins in FIGS. 1 through 5 and a cable cord in FIGS. 1, 2, and 4 through 6 are for illustrative purposes only and form no part of the claimed design.
